TOY PISTOL

Bernard Lindenbaum, Dayton, Ohio

Application May 5, 1948, Serial No. 146,192

Term of patent 3½ years

(Cl. D34—15)

To all whom it may concern:

Be it known that I, Bernard Lindenbaum, a citizen of the United States, residing at Dayton, in the county of Montgomery and State of Ohio, have invented a new, original, and ornamental Design for a Toy Pistol, of which the following is a specification, reference being had to the accompanying drawing, forming part thereof.

In the drawings,

Figure 1 is a perspective view of a toy pistol, showing my new design;

Figure 2 is a side elevational view thereof, as seen from the side opposite the slot for the firing bolt;

Figure 3 is another side elevational view, disclosing the slot for the firing bolt;

Figure 4 is a top plan view thereof;

Figure 5 is a bottom view;

Figure 6 is a front elevational view and

Figure 7 is a rear elevational view.

I claim:

The ornamental design for a toy pistol, as shown.

BERNARD LINDENBAUM.
